FIG. 4.

FIG. 5.

Patented Jan. 19, 1926.

UNITED STATES PATENT OFFICE.

WALTER P. FRITSCHÉ AND JOHN DIEHL CLARKE, OF NEW HAVEN, CONNECTICUT.

AIR BOAT.

Application filed January 14, 1925, Serial No. 2,324. Renewed November 12, 1925.

To all whom it may concern:

Be it known that we, WALTER P. FRITSCHÉ and JOHN DIEHL CLARKE, citizens of the United States, residing at New Haven, 5 in the county of New Haven and State of Connecticut, have invented certain new and useful Improvements in Air Boats, of which the following is a specification.

This invention relates to improvements 10 in boats and it consists of the constructions, combinations and arrangements herein described and claimed.

An object of the invention is to provide 15 an inflatable boat in the nature of a raft having, as one of the features of novelty, an arrangement of double air chambers such provision insuring the preservation of the shape of the boat in the event of the deflation of one of the chambers.

Another object of the invention is to provide 20 a pneumatic boat having a bottom to which the air chambers are secured, providing for a uniform distribution of the load over a considerable area, reducing the 25 stresses on the air chambers and dispensing with the need for wood and metal reinforcements.

Another object of the invention is to provide 30 adequate joints of particular construction.

A further object of the invention is to provide 35 a double bottom in a boat of the character described, permitting an increase of load when the compartment thus formed is inflated, and providing additional comfort when the boat is used for sleeping purposes.

Other objects and advantages appear in 40 the following specification reference being had to the accompanying drawings, in which:

Figure 1, is a plan view of the improved boat,

Figure 2, is a longitudinal section on the line 2—2 of Figure 1,

Figure 3, is a detail enlarged section of 45 a portion of the boat,

Figure 4, is a detail longitudinal section of a portion of the air chambers showing how a joint is made,

Figure 5, is a detail view of one of the oar 50 locks in completed condition,

Figure 6, is a detail view illustrating the steps of making the oar lock,

Figure 7, is a section illustrating the use 55 of a double bottom for purposes stated, and

Figure 8, is a detail view of one of the separable oars which may be carried with the boat.

In carrying out the invention provision is 60 made of a relatively large sheet of material 1, providing a floor for the boat. Air chambers 2 and 3 are disposed at the periphery of the floor. The floor constitutes a partition which divides the pneumatic rim of 65 the boat into the two air chambers mentioned. The floor divides the boat centrally, providing a receptacle of equal depth whether the boat is launched either side up.

The air chambers are capable of independent inflation at valves 4 and 5 providing an item of safety of no small importance. Should one of the chambers become deflated, as by puncture, etc. there will still be an inflated chamber which will preserve the 75 shape of the boat and render it capable of still floating.

Each end of the chamber fabric is turned under at 6 and 7 respectively. These ends are suitably secured to the floor sheet 1 upon which they lap. Cementing, sewing or the like may be employed. A strip 8 of rubberized tape is applied to the seam on the outside of the boat, corner strips 9 and 10 being applied on the inside. The various arrangements are intended to secure the joints so that no air can escape from the chambers.

The combined effect of the air chambers is that of a tube. The tubular, double air rim is composed of sections, as well shown 80 in Figure 1 without specific designation by reference characters. The sections are telescoped as at 11 in Figure 4. The telescoping joint is secured by a tape 12. These joints are usually fitted and taped before the tapes 85 8, 9 and 10 (Fig. 3) are applied, the latter subsequently cover the former and serve to hold them down.

Oar locks 13 and 14 hold the oars while 100 rowing. One of the oars 15 is shown in Figure 8. The oar is separable at 16, permitting removal of the handle 17 for storing of the oar in a small space. The oar locks are shown provided in duplicate on opposite sides of the boat. This arrangement, although not essential, is nevertheless useful because in the haste attending an emergency the boat may be thrown overboard upside down. In such event a single pair of oarlocks would be inaccessible.

Each of the oarlocks is made of a plurality of strips 15 and 16 of webbing (Figs. 5

and 6), cemented together and sewed at 17. The ends of the webbing are turned in opposite directions at 18 and 19 (Fig. 5) and suitably secured to the air chamber casing. The latter ends are additionally held down by a shield or covering 20.

Figure 7 illustrates the incorporation of an additional feature in the boat. The extra bottom 21 provides a mid-compartment 22 which is intended to be filled with air through a valve 23. The edge of the extra bottom is secured by a cemented tape 24 on the outside and a tape 25 on the inside. The remaining parts of the boat are the same as in the other views, similar reference characters being used.

It is to be noted that the bottom 1 of the boat, instead of being suspended from or attached to the air chamber, forms a platform or base to which the air chambers 2 and 3 are attached. Any load imposed upon the bottom is distributed over a large area, and the manner of construction greatly reduces the stresses on the air chambers. All wood and metal reinforcements are dispensed with.

The buoyancy of the boat is increased for additional loads or emergencies by the additional bottom 21 (Fig. 7) and the inflatable compartment 22 that it provides. This compartment, when inflated, furnishes a boat in which there is a triple measure of safety. When used as a bed, the boat in Figure 7 provides additional comforts.

There is some choice as to the material of which the boat is made, but the material most desired is a specially manufactured airship fabric. This is made to withstand high pressures and severe handling without being unduly heavy.

We claim:

1. A structure of the character described comprising a member constituting a floor, and an inflatable rim upon the floor, being divided by the floor to provide double and independent air chambers.

2. A structure of the character described comprising an inflatable body, a floor for the structure extending through said body forming a partition dividing it into two air chambers, and means through which said chambers are separately inflated.

3. A boat comprising a floor, and a pneumatic rim upon the floor, said floor extending through the rim and dividing it into separate air chambers, said floor preserving

the shape of the boat and maintaining the integrity of the other chambers in the event of deflation of the other.

4. A boat comprising a floor, a pneumatic rim upon the floor composed of half sections each of which constitutes a separate air chamber by virtue of being divided by the floor, and joint-securing means affixed to adjacent section and floor parts at the seams.

5. A boat comprising a foundational floor preserving the shape of the boat, and an air container affixed to and divided in a plurality of air chambers by said floor.

6. A boat comprising an air container, a floor for the boat dividing the container into a plurality of separate air chambers, independent valves permitting filling the respective chambers from adjacent sides of the floor, and duplicate sets of oarlocks on opposite sides of the boat providing for use of the boat when launched either side up.

7. A boat comprising an air container, and a floor situated in a central, horizontal plane in respect to the container, dividing the container into a pair of air chambers and providing a receptacle of equal depth when launched either side up.

8. A boat comprising a floor, an air container composed of sections having the ends turned in and lapped upon the floor, joint-closing means including a tape attached to said sections over the edge of the floor to close the seam, and other joint-closing means including tapes attached to said sections and floor on the inside of the boat.

9. A boat of the character described comprising an air container composed of sections telescopically fitted together, and means to secure the joint including a tape applied on the outside.

10. A boat having an oarlock composed of strips of webbing the ends of each of which are turned in opposite directions for attachment to a support, means including stitching securing the strips together, and means including a shield applied over the remote turned ends to hold them down upon said support.

11. A boat having a foundational floor, and air container so mounted upon the floor to be divided thereby into independent air chambers, and an extra floor affixed to the container at one side providing an additional inflatable compartment.

WALTER P. FRITSCHE.
J. DIEHL CLARKE.
